UNITED STATES PATENT OFFICE.

DANIEL R. SHERWOOD, OF PLAINFIELD, AND JOHN KARITZKY, OF GARWOOD, NEW JERSEY, ASSIGNEES TO HENRY B. NEWHALL, JR., OF PLAINFIELD, NEW JERSEY, EXECUTOR OF HENRY B. NEWHALL, DECEASED.

SPRING-TOGGLE.

1,374,959.

Specification of Letters Patent. Patented Apr. 19, 1921.

Application filed December 23, 1919. Serial No. 347,039.

To all whom it may concern:

Be it known that we, DANIEL R. SHERWOOD, a citizen of the United States, residing at Plainfield, in the county of Union and State of New Jersey, and JOHN KARITZKY, a citizen of the United States, residing at Garwood, in the county of Union and State of New Jersey, have invented certain new and useful Improvements in Spring-Toggles, of which the following is a specification, taken in connection with the accompanying drawings.

Our invention relates to toggles. More particularly it relates to means which will insure that the toggle head will rock or swing at an angle to the arm or bolt, after it has been inserted into the wall or other support.

Our invention further relates to a toggle having a head provided with pivoting means midway its length, so that one end does not overbalance the other, and means to insure the rocking of the toggle head when it has been inserted in the wall.

Our invention further relates to a rigid toggle head which is swung upon the pivoting nut by spring means carried by the nut. Our invention also covers the spring, as a separate article of manufacture, which may be sold separately and be applied to the toggle by the user.

Our invention further relates to certain combinations and details of construction which will be more fully hereinafter described in the specification and pointed out in the claims.

In the accompanying drawings the same reference numerals refer to similar parts in the different figures.

Figure 1 is a perspective view of our spring toggle bolt, one of the flanges being omitted from the toggle head for purpose of clearer illustration;

Fig. 2 is a vertical section through a wall or other support, and the work to be supported, showing the manner of positioning the spring toggle which is shown in side elevation;

Fig. 3 is a vertical section through a wall or other support and the work supported, the same as in Fig. 2, but showing the toggle head rocked at right angles to the bolt by means of the spring carried by the nut;

Fig. 4 is a perspective view of the preferred form of spring which we employ; 55

Fig. 5 is a perspective view, partly broken away, showing our invention applied to a toggle now on the market in which one end of the head is longer than the other so that gravity will have a tendency to rock it upon 60 the nut;

Fig. 6 is a perspective view, partly broken away, the same as in Fig. 1, but showing the coil spring provided with only one arm instead of two as in the preferred construc- 65

In the toggle bolts now on the market it is customary to pivot the arm or bolt to the head so that one end of the head is heavier than the other. That is, the pivot is not located substantially midway between the ends of the head. By having one end longer, that end will be heavier than the other end, and consequently will have a tendency to overbalance it and cause the toggle head, as 75 soon as it is pushed home, to assume an angle to the arm or bolt to which it is pivoted. A very slight obstruction inside the wall or support however will prevent gravity turning the head at right angles to the 80 hole, so that the work can be secured to the wall. Such toggle heads also have been found objectionable in practice in that a comparatively long head has to be used to obtain the overbalancing feature. 85

By our invention we positively insure that the toggle head will assume a position at an angle to the hole, through which it has been inserted, even though it should scrape upon some slight obstruction which would be sufficient to prevent the ordinary form of gravity toggle from operating. Further we can make our toggle head of minimum length which will not only save metal, and therefore cost of manufacture, but it will 95 permit our toggle to be used in thin partitions, or similar walls or structures, where the free space in which the toggle has to turn or swing is too limited for the ordinary gravity toggle which has to be of unnecessary length to obtain the overbalancing feature. 100

In our invention the toggle head is rigid and preferably formed of one piece of sheet metal, which gives the maximum strength 105 in spanning the opening in the wall.

- In the illustrative embodiment of our invention as shown in the drawings, 1 is a toggle head having a base 2, and flanges 3, 3 one of the flanges being omitted in Fig. 1. 5 In the preferred construction we mount a nut 6 having trunnions 7, 7, midway between the ends 4 and 5 of the toggle head 1. These trunnions 7, 7 are received in openings or bearings 8, 8, punched or otherwise 10 formed in the flanges 3, 3.
- In our invention we employ spring means carried by the nut 6 to cause the toggle head 1 to swing at right angles to the bolt 9. Various forms of spring means carried by 15 the nut may be employed. We have shown as one embodiment of our invention a spring 10, Fig. 4, formed of wire, or other suitable material, bent back upon itself to form a coil 11 to receive the bolt 9, the two ends 20 12, 12 are then bent down from the coil substantially parallel to each other and then bent at the points 13, 13, 14, 14, 15, 15 and 16, 16 so as to form, in effect, an open cage 17 within which the nut 6 is yieldingly held. 25 The arms 12, 12 are then brought parallel to each other as shown in Fig. 4 and 1. The nut 6 is inserted within the pocket 17 by simple manipulation where it is yieldingly held; the nut 6 and spring 10 move together. 30 In using our invention the bolt 9 may be passed through the work 18, or other suitable article to be supported on the wall or other suitable support 19, the end of the bolt being passed through the coil 11 into 35 engagement with the threads of the nut 6. By bending down the end 5 of the toggle head so that it will come into alignment with the bolt 9, the toggle head 1 can be inserted within the hole 20 in the support or 40 wall 19. This places considerable tension upon the spring 10, the free arms 12, 12 of the spring bearing upon the inside of the toggle head 1. As soon as the end 5 escapes the inner surface 21 of the wall or other 45 suitable support 19, the spring 10 will throw the toggle head 1 sharply at right angles to the bolt 9 as shown in Fig. 3. The work 18 is then securely held to the face 22 of the wall by simply screwing up the bolt 9. 50 While we preferably use two free arms 12, 12 of the spring 10 to bear upon the inner surface of the toggle head we may use simply one such arm as shown for example in Fig. 6.
- 55 Our invention may also be employed with toggle bolts in which the toggle head 23, Fig. 5 has one end 24 longer than the end 25 so that gravity will have a tendency to rock the head 23 with relation to the bolt 9. In this form our spring, carried by the nut 6, serves to accentuate and make sure the action of gravity by causing the arm 12, 12 to kick over the end 25 of the toggle bolt,

when it escapes the inner surface 21 of the wall or other suitable support 19.

65

Having thus described this invention in connection with illustrative embodiments thereof, to the details of which we do not desire to be limited, what is claimed as new and what is desired to secure by Letters 70 Patent is set forth in the appended claims.

What we claim is:—

1. In a toggle, the combination of a one piece head, a bolt, a nut, and a spring carried by the bolt and embracing the nut 75 and adapted to rock the one piece head with relation to the bolt.

2. In a toggle, the combination of a one piece head, a bolt, a nut, and a spring carried by the bolt and embracing the nut and 80 having one or more free arms and adapted to rock the one piece head with relation to the bolt.

3. In a toggle, the combination of a one piece head, a nut, and a spring embracing 85 the nut.

4. In a toggle the combination of a one piece head, having bearings for a nut, a nut mounted on said bearings and a spring 90 yieldingly embracing the nut, adapted to move with it and adapted to rock the one piece head.

5. In a toggle the combination of a one piece head, having bearings for a nut, a nut mounted on said bearings and a spring 95 yieldingly embracing the nut, adapted to move with it and adapted to rock the one piece head, said spring having a portion adapted to receive a bolt.

6. In a toggle the combination of a one 100 piece head having bearings for a nut, a nut mounted on said bearings, and a spring yieldingly embracing the nut, said spring being provided with one or more arms bearing on the head and adapted to rock it.

105

7. An article of manufacture for a toggle comprising a spring having a central portion to receive a bolt, a cage to surround a nut, and one or more free arms.

8. An article of manufacture comprising 110 a toggle head, a bent wire spring having a coil portion to receive the bolt, a bent portion to substantially surround and embrace a nut, and one or more free arms.

9. In a toggle, the combination of a head, 115 a nut on which the head is pivoted, a spring cage having one or more arms extending in the same direction, the spring cage adapted to surround the nut and having one or more of its arms adapted to bear on the same side 120 of the pivot.
